COMBINATION IMPLEMENT

Application filed May 2, 1929. Serial No. 359,908.

The present invention appertains to new and useful improvements in combination implements, and more particularly to a novel combination of clothes prop and clothes line cleaner. The principal object of the invention is to provide a novel clothes prop which can be adjusted for use with clothes lines of varying height.

Another object of the invention is to provide a clothes prop which may be employed for supporting means for cleaning a clothes line.

These and other important objects of the invention will become more apparent to the reader after considering the invention as described and claimed hereinafter.

In the drawings:

Figure 1 represents a view disclosing the implement being employed for cleaning a clothes line.

Fig. 2 represents a fragmentary side elevational sectional view.

Fig. 3 represents an enlarged fragmentary edge elevation of the structure.

Fig. 4 represents a fragmentary side elevational view of the device.

Referring to the drawings wherein like numerals designate like parts, it will be seen that the present invention as a clothes line prop, includes a pair of elongated bars 5 and 6. One of said bars is provided with a pointed end 7 and this part is also provided throughout its major portion of its intermediality with a longitudinally extending slit 8.

The end portion of the complementary bar 6 adjacent the pointed end 7 of the bar 5 has a threaded member 9 protruding therefrom and through the slit 8. A wing nut 10 is engageable on the threaded member 9 for clamped engagement against the outer side of the bar 5 for maintaining the two bars in a set position.

A U-shaped guide member 11 has the end portions of its leg 12—12 secured to the opposite end portion of the bar 5, while the adjacent end portion of the bar 6 is slidable through the guide 11 and is provided with a V-shaped notch 13 into which the clothes line 14, shown in Figure 1 may be engaged, when the device is employed as a prop.

However, the present invention provides means whereby the clothes line may be easily cleaned. To this end, a U-shaped member 15 has its leg portions 16—16 secured to the bar 5 adjacent the notched end 13 of the bar 6 and this U-shaped member is disposed in the slightly oblique manner clearly shown in Figures 3 and 8. For having the member disposed in this manner, the same may be engaged over a clothes line in a manner shown in Figure 7 without likelihood of the same becoming easily disengaged. A cloth strip 17 is engaged over the bight portion of the member 15 and is draped over the clothes line 14 in the manner clearly shown in Figure 7 so that by sliding the member 15 along the clothes line, the latter will be efficiently cleaned.

It will thus be seen that we have provided a combination adjustable clothes prop and clothes line cleaner, and it is contended that this device can be manufactured at a very low cost and retailed at a price well within the economic demand of the public for such an article. Obviously, numerous changes in the specific shape, size, and materials may be resorted to in the construction of the novel device without departing from the spirit and scope of the invention as claimed hereinafter.

Having thus described the invention, what we claim as new and desire to secure by Letters Patent is:—

A clothes line cleaner comprising a handle, a laterally projecting rigid U-shaped member adjacent one end of the handle, said member being adapted to have a cloth disposed about the bight portion thereof, the arms of the U-shaped member forming an acute angle with the handle, whereby the clothes line may be readily retained in the crotch formed between the arms and the handle, the cloth being disposed so that it presses on the clothes line on one side, the U-shaped member and handle on the other side affording a backing for the cloth to resist movement thereof.

In testimony whereof we affix our signatures.

STEPHEN J. BRUTOFSKI.
JOHN ARMSTRONG.
LOUIS SHERMAK.
